UNITED STATES PATENT OFFICE

96,867

DESIGN FOR A DISPLAY STAND OR THE LIKE

James Stipek, Cicero, Ill.

Application April 22, 1935, Serial No. 56,497

Term of patent 7 years

To all whom it may concern:

Be it known that I, James Stipek, a citizen of the United States of America, residing at Cicero, in the county of Cook and State of Illinois, have invented a new, original, and ornamental Design for a Display Stand or the like, of which the following is a specification, reference being had to the accompanying drawing, forming a part thereof.

In the drawing:

Fig. 1 is a front elevational view of the display stand showing my design. Fig. 2 is a top plan view. Fig. 3 is a side elevational view. Fig. 4 is a perspective view.

What I claim is:

The ornamental design for a display stand or the like, as shown.

Signed at Chicago, Cook County, Illinois, the 18th day of April, 1935.

JAMES STIPEK,
